to all whom it may concern

Be it Known that we, G. Warren S. H. Swallow and R. C. Little, of Boston in the County of Suffolk, and State of New-England, have invented or produced a new and original design of Book-Store plates, which we call the "Morning Star" and we do hereby declare, that the following is a full, clear and exact description of the same, reference being had to the annexed drawings making a part of this Specification, of which

Figs. 1, 2, & 3 is a plan and sectional view of the jamb plate

Figs. 4, 5 & 6 is a plan and sectional view of the front plate and

Figs. 7 & 8 plan and sectional view of top plate.

Our design of Stone plates is as follows: in it is the jamb plate with the mouldings (a) at top and bottom (b) are over doors the edges finished with the moulding (B) and the panels ornamented with the rosettes (C) and stars (d) lozenges (e) &c in the fire door decorated on the panel with the diamond work ornament (F) & is the front plate with the moulding (g) at top the fire doors (E) are decorated on the panels with the diamond work ornaments (H) and finished at the edge with the moulding (i). & is the top plate with the edge moulding (j)

Having . . . . described our design of book store plates.

What we claim as new and desire to secure by Letters Patent, is the ornamental design and configuration of book-Store plates, which was herein described.
